Claims priority, application France Sept. 11, 1959
6 Claims. (Cl. 19—225)

This invention relates to rectilinear combers for textile fibers, especially for short staple fibers such as cotton.

More particularly the invention relates to combing machinery having a combed fiber take-off device comprising rolls between which the combed fibers are passed and an oscillating nipper with lower and upper jaws for pressing together and retaining the fibers at the time when their leading ends are combed.

In conventional practice, the take-off devices of such machines have two pairs of rolls of substantially equal diameter as shown in FIG. 1. Such an arrangement has disadvantages. For one thing, the separation of the axes of the rolls of each pair, which determines the distance over which the fibers are nipped, must be short and the more so, the shorter are the fibers to be treated. Also, the room available for disposal of the rolls, due to the need to bring the two pairs of rolls close to one another, is small and this too severely limits the diameters of the rolls, with the result that they are subject to flexure. This disadvantage is enhanced by the need to cover one roll at least of each pair with a flexible, elastic material, the thickness of which reduces correspondingly the diameter of the rigid metallic core of the roll, whose outside diameter is limited as stated above by the required closeness of the axes of the rolls of each pair. Thus, the thickness of the flexible, elastic covering is severely limited by the need to make the roll stiff enough and a desired degree of suppleness of the covering cannot easily be achieved.

With rolls of small diameter their angular velocity must be high to achieve the necessary peripheral speed. This raises further difficulties because of the continual reversals of rotation of the rolls during the combing operation.

Moreover, the rolls of each pair must rotate at strictly equal peripheral speeds and this gives rise to further difficulties.

One object of this invention is to provide a comb whose fiber take-off device is free from the above-mentioned disadvantages.

A more particular object of the invention is to provide a fiber take-off device for a rectilinear comb comprising a single lower driving roll of relatively large diameter and in contact therewith two upper idler pressure rolls of relatively small diameter.

With such a device, the same peripheral speed requires a considerably lower angular velocity of the lower driving roll than the angular velocities of the two pairs of rolls of a comparable conventional device. This simplifies the problems of reversal of rotation of the driving roll whose kinetic energy is much less. Furthermore, the problem of equalizing the peripheral speeds of independent rolls no longer arises, as there is but one driving roll, which drives the other two by frictional contact.

The necessary flexible, elastic covering may be applied to the lower driving roll leaving the two smaller metallic idler rolls bare thus enabling the latter to be made stiff enough while keeping their diameter small enough to obtain the required short length of nip and at the same time enabling the flexible covering (of the large driving roll) to be made as thick as may be required.

It is further desirable to keep the "sorting base" i.e. the distance between the jaws of the nipper and the nip

2

of the pressure roll nearest the nipper, as nearly constant as possible, since this improves the combing performance.

Accordingly, a still further object of the invention is to provide a fiber take-off device in which means are provided for displacing the nip of the idler pressure roll nearest the nipper concentrically of the driving roll once per cycle of the machine, so that it follows the nipper for part at least of the latter's stroke; and achievement of this further object is facilitated by the construction forming an object of the invention comprising a single driving roll of relatively large diameter, which construction moreover makes it comparatively easy for the beak of the lower jaw of the nipper to follow a path concentric with the periphery of the driving roll over a considerable portion of its stroke as it reciprocates substantially tangentially to the periphery of a circular comb from and towards a predetermined tangent point thereof. An arrangement having this effect constitutes yet another object of the invention.

20 How the foregoing objects of the invention and such others as may hereinafter appear may be practically achieved and the nature of the invention generally will be more fully understood from the following description having reference to the accompanying drawings of embodiments of the invention, given by way of example only and without implied limitation of the scope of the invention, which is defined in the appended claims.

In the drawings:

FIGURE 1 is a schematic illustration of the rolls of 30 a conventional fiber take-off device for a rectilinear comb;

FIGURE 2 illustrates schematically an arrangement of the driving and idler-pressure rolls of a fiber take-off device according to the present invention;

35 FIGURE 3 is a view similar to FIGURE 2 illustrating a modification;

FIGURE 4 illustrates in side elevation the complete assembly of another embodiment; and

FIGURE 5 illustrates a detail of FIGURE 4 on an 40 enlarged scale.

Referring to FIGURE 2, the combed fiber take-off device of the rectilinear comb comprises a lower driven metallic roll 11 covered with a thick layer of flexible-elastic material of relatively large diameter 12 and two 45 upper idler-pressure rolls 13, 14 of equal and relatively small diameter closely coupled together by means of side plates 16 in which they are rotatably mounted, pressure being applied to the plates 16 in the direction of the straight arrow.

50 In the arrangement of FIGURE 2, the rolls 13, 14 are made of metal and are bare, thus developing the maximum stiffness corresponding to their diameters.

Because of its relatively large diameter, the angular velocity of the driving roll 11, 12 for a given peripheral 55 speed is relatively low and consequently the inert effects, which come into play every time the direction of rotation of the roll is reversed, and which are proportional to the square of the angular velocity, are considerably reduced when compared with those of a conventional arrangement

60 having small diameter rolls as illustrated in FIGURE 1. Moreover, the large diameter of the roll 11, 12 considerably simplifies the design and construction of the differential controlling mechanism (not illustrated) which imparts to the roll an intermittent motion in which more 65 extensive forward rotational displacements alternate with less extensive rotational displacements in the return direction.

Again, because of the large diameter of the roll 11, 12, the thickness of its flexible elastic covering 12 is not 70 limited by considerations of stiffness and can be made as great as may be required to provide the desired suppleness and it does not depend on the length of nip, that

is to say, the distance between the points of contact of the rolls 13, 14 with the roll 11, 12.

Since both the rolls 13, 14 are frictionally driven by the roll 11, 12, their peripheral speeds are necessarily strictly equal.

The close coupling of the rolls 13, 14 enables the length of the nip to be made short and this is particularly valuable when dealing with short staple fibers, such as cotton.

In the modification illustrated in FIGURE 3, the pressure rolls 13a, 14a are covered with layers 13b, 14b of flexible elastic material with the driving roll 11a free of such covering thereby having a hard surface in which is formed longitudinal grooves 15. Although the flexural stiffness of the pressure rolls 13a, 14a is somewhat reduced by the reduced diameters of their metallic cores, the high degree of friction exerted by the grooves 15 on the coverings 13b, 14b of the rolls 13a, 14a provides a somewhat better entrainment of the fibres than the arrangement of FIGURE 2.

Referring again to FIGURE 2, the distance between the axes of the pressure rolls 13, 14 is constant as the same is fixed by the side plates 16 carrying the rolls.

In the arrangement illustrated in FIGURES 4 and 5, however, the distance between the axes of the rolls 13, 14 is variable, being controlled by a mechanism designed to keep substantially constant the sorting base (previously defined) at least during an appreciable fraction of the stroke of the nipper.

In the construction illustrated in FIGURES 4 and 5, the idler-pressure roll 14 remote from nipper N is mounted by means (not illustrated) so that the position of its axis is fixed, while the pressure roll 13 nearest the nipper is mounted for rotation on one end of a curved lever 17 whose other end is pivotally mounted at 18 on an oscillating arm 19 pivotally mounted at 20 on a fixed part of the machine. The lever 17 is loaded by spring 39 which applies the contact pressure between the rolls 13 and 11. The arm 19 is rigidly connected to another arm 21 which is connected by a crank pin 22 to one end of a link 23 whose other end is similarly connected at 24 to one limb of an oscillating fork 25 which pivots freely about a shaft 26 from which the nipper is suspended by means of an arm 29 fast on the shaft 26. The other limb of the fork 25 carries a roller 31 which engages in a groove 32 in the form of a closed loop formed in a cam 33 which is driven continuously at uniform rotational speed by a transmission from the main driving shaft of the machine (not illustrated) at the rate of one revolution per combing cycle.

The circular comb per se is shown at 34 with its needles being indicated at 35.

The nipper N comprises a lever constituting upper jaw 27 and a lower jaw 28 terminating in a beak 38 with both jaws being pivotally mounted at 30 on the suspension arm 29. The jaws 27, 28 have rearward extensions or arms 27a, 28a and are thereby substantially equilibrated about their pivot 30 in the manner of a balance beam.

The paths followed by the jaws 27, 28 are determined by guiding means constituted by fixed guide tracks 41, 42 of suitable profile engaged by rollers 43, 44 carried respectively by the extensions 27a, 28a of the jaws 27, 28.

FIGURE 5 illustrates the movements of the nipper and of the pressure roll 13 with the elements 13, 17, 27, 28 being shown in full lines when at one extreme position of their movements and in chain dotted lines at the positions occupied by them after an appreciable retraction of the nipper from the said extreme position. In moving along the periphery of the roll 11 from full-line position to the chain-dotted line position, the axis of roll 13 describes an arc of angular extent and about the axis of the shaft 36 carrying the roll 11. This movement takes place in synchronism with the rearward displacement of the nipper jaws 27, 28 from the full-line position to the chain-dotted

line position with these displacements of the roll 13 and nipper jaws 27, 28 being such that the sorting base, i.e. the distance between the nip of roll 13 and the peak 38 of the lower nipper jaw 28 remains substantially constant during the rearward movement of the nipper. Co-ordination of the motions of the roll 13 and the nipper N is ensured by a suitable choice of the profiles of the cam groove 32 and of the guides 41, 42. The relatively large diameter of the driving roll 11 enables the extent of the displacement of the nipper jaws 27, 28 over which the sorting base remains substantially constant to occupy a considerably larger fraction of the total displacement of the nipper jaws than is possible with the conventional arrangements of rolls as illustrated in FIGURE 1. Moreover, the large diameter of roll 11 makes it possible for the nipper jaws to follow a path corresponding closely to the surface of the driving roll, a result of which is impossible or difficult of attainment with conventional arrangements as illustrated in FIGURE 1.

It is to be understood that the invention is not limited to the particular form of constructions illustrated in the drawings, but is susceptible of numerous modifications and variants within the competence of those skilled in the art, without thereby departing from the spirit and scope of the invention as defined in the hereto appended claims.

Having thus described the invention, what is claimed as new and desired to be secured by Letters Patent is:

1. In a rectilinear combing machine, in combination, a circular comb, a detaching mechanism comprising opposed upper and lower rolls with the lower roll being of greater diameter than the upper roll and a forwardly and backwardly swinging nipper arrangement co-operating with said detaching mechanism, said nipper arrangement including a suspension rod having upper and lower ends, means pivotally securing the upper end of the suspension rod about a fixed point of the machine located above the axis of said circular comb, two substantially horizontal nipper levers, each lever having arms, said levers being fulcrumed in substantially stable equilibrium on a common pivotal point at the lower end of said suspension rod, one of said nipper levers comprising an upper nipper jaw and the other nipper lever a lower nipper jaw, one arm of one of said levers carrying the upper jaw and one arm of the other lever carrying the lower jaw of said nipper arrangement, means to impart swinging motion to said suspension rod about said fixed point to thus move the nipper levers relatively to the periphery of the circular comb, and means to guide the other arms of said two levers each along one of two distinct arcuate paths respectively, one of said two paths being designed so that said lower jaw reciprocates substantially tangentially to the periphery of said circular comb from and towards a predetermined tangent point thereof and further describes an arc substantially concentric to said lower roll and the other path being designed so as to produce opening and closing movement, respectively of said upper jaw relatively to the lower jaw as the latter reciprocates from and towards said tangent point.

2. A rectilinear combing machine as claimed in claim 1 further including a second upper roll located closer to said jaws than the first mentioned upper roll, and means for oscillating said second upper roll in a path concentric to said lower roll.

3. A rectilinear combing machine as claimed in claim 2 in which said last-named means is operative to maintain substantially constant the distance between the lower jaw and the point of contact of said second upper roll on said lower roll at least during a part of the movement of said lower jaw away from said first mentioned upper roll.

4. A rectilinear combing machine as claimed in claim 1 including a second upper roll located closer to said jaws than the first mentioned upper roll, lever means having opposite ends, means mounting said second upper roll at one end of said lever means, spring means operably

connected to the lever means to apply said second upper roll with pressure against said lower roll, a rocking arm, means pivotally connecting the other end of the lever means to said rocking arm, a cam mechanism for imparting to said rocking arm a to-and-fro oscillation of limited extent once in each complete combing cycle, and means actuated by said cam mechanism for oscillating said jaws.

5. A rectilinear combing machine as claimed in claim 4 said last-named means comprising transmission means operably connecting said cam mechanism to said rocking arm and nipper levers, respectively, so constructed and arranged that the distance between the lower jaw and the point of contact of said second upper roll on said lower roll remains substantially constant at least during a substantial part of the movement of said lower jaw away from said first mentioned upper roll.

6. A rectilinear combing machine as claimed in claim

4 in which said cam mechanism includes a cam rotatable at the rate of one revolution per combing cycle, a cam follower, said last-named means comprising transmission means for connecting said cam follower with said rocking arm and said suspension rod.
